UNITED STATES PATENT OFFICE.

FRANK W. LIERMAN, OF MILWAUKEE, WISCONSIN; AUGUSTA LIERMAN EXECUTRIX
OF SAID FRANK W. LIERMAN, DECEASED.

POWER-GENERATING APPARATUS.

964,923.

Specification of Letters Patent. Patented July 19, 1910.

Application filed April 15, 1908. Serial No. 427,122.

To all whom it may concern:

Be it known that I, FRANK W. LIERMAN, a citizen of the United States, residing at Milwaukee, in the county of Milwaukee and 5 State of Wisconsin, have invented certain new and useful Improvements in Power-Generating Apparatus, of which the following is a specification.

A serious objection to the combustion of fuel within the cylinder of a motor, as is done in the ordinary internal-combustion engine, is that much of the heat generated is lost in the cooling water or other fluid required to keep the cylinder at a proper working temperature. The burning of the fuel in the engine cylinder incidentally introduces serious difficulties in properly lubricating the moving parts. The explosion of combustible gases in the engine cylinder also 15 renders it difficult, if not impossible, to obtain that regularity of impulse which is obtainable in motors of the well known double-acting steam engine and turbine types.

My invention contemplates a power-generating apparatus in which the difficulties hereinbefore outlined, among others, are obviated.

In an apparatus embodying my invention, the fuel is burned, not in the engine cylinder, but in a separate furnace or combustion chamber, and the products of combustion are conducted to the motor, where they perform work in expanding. Combustion is supported and the products of combustion 30 diluted to reduce them to a temperature suitable for use in the motor, by means of air supplied to the furnace by an air compressor which may be operated by the motor.

The accompanying drawing is a diagrammatic representation of an apparatus embodying the features of my invention.

The generator 1 comprises an air-tight container which may be divided by a partition 2 into an air chamber 3 and a combustion and expansion chamber 4. The present embodiment, which is especially intended for use with hydrocarbon or other liquid fuel, comprises a spraying nozzle 5 that is mounted in the axial center of the combustion and expansion chamber 4 at a little distance above the floor 6 thereof. Surrounding the spraying nozzle 5 is a basin 7 for confining the drippings or overflow of the fuel oil. Above the spraying nozzle 5 is a fire hood 8 which may be supported from

the partition 2 and connected with the interior of the air chamber 3 by a tube 9.

A fuel reservoir 10 is located in any suitable place at a point above the spraying nozzle 5, and is connected with the latter by means of a supply pipe 11 in which is located a cut-off valve 12. A needle valve 13 is located at a suitable point in the pipe 11, is actuated by means to be hereinafter described to control the production of pressure fluid.

The combustion and expansion chamber 4 is connected with a motor 14 by means of a pipe 15 in which a cut-off valve 16 may be provided. Said motor may be of any common or suitable type, as, for example, a double-acting reciprocating engine, as shown. An air compressor 17, of any preferred type and driven from a suitable source of power, such as the motor 14, is connected with the air chamber 3 by means of a pipe 18 and with the oil reservoir 10 above the level of the oil by means of a pipe 19.

The needle valve 13 is operated by the governor 20 of the motor 14 or controlled by said motor in any other suitable way.

Combustion may be started by means of an electric igniter 21 arranged to ignite the hydrocarbon in the basin 7 or the vapors rising from said hydrocarbon.

22 is a safety valve upon the generator 1. Before putting the apparatus in operation, the generator 1 is filled with a sufficient quantity of air to maintain combustion until the pressure in the generator is raised to the point where it can be utilized in the motor. When the valve 12 is opened, the fuel oil flows into the basin 7 where it is ignited by means of the electric igniter 21. The heat generated and the vaporization of the fuel causes the pressure of the contents of the generator to rise to a point where they are adapted for use in the motor. The valve 16 is then opened, admitting the pressure gases to the motor. The operation of the latter causes the air compressor 17 to be operated to deliver air to the air chamber 3.

I aim to obtain in the generator 1 practically perfect oxidation of the fuel, the pressure fluid passing to the motor being a mixture of carbon dioxid, nitrogen and steam, but under certain working conditions a relatively small portion of the oxygen of

the air supplied to the generator may pass over to the motor.

The temperature in the fire hood 8 approximates the temperature of combustion, but the temperature of the products of combustion is reduced through dilution with atmospheric nitrogen and through expansion in the chamber 4 prior to their passage to the motor.

10 Obviously the area of the compressor plunger or piston must be less than the area of the engine piston.

I claim as my invention:

15 A pressure-fluid generator comprising an upper and a lower chamber, the upper one being an air chamber and the lower a com-

bustion and expansion chamber, means for supplying air to said air chamber, a burner in the lower part of said combustion chamber, means for supplying fuel to said burner, 20 a hood overhanging said burner, a connection between said hood and said air chamber adapted to direct a blast of air upon said burner, and an outlet in said combustion chamber at a point remote from said burner, for the mingled air and products of combustion.

FRANK W. LIERMAN.
